US0D1085153S

(12) **United States Design Patent** (10) **Patent No.:** **US D1,085,153 S**
(45) **Date of Patent:** **** Jul. 22, 2025**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Woonghee Lee**, Suwon-si (KR); **Younga Kim**, Suwon-si (KR)

(73) Assignee: **SAMSUNG ELECTRONICS CO., LTD.**, Suwon-si (KR)

(**) Term: **15 Years**

(21) Appl. No.: **29/832,851**

(22) Filed: **Mar. 30, 2022**

(30) **Foreign Application Priority Data**

Oct. 15, 2021 (KR) 30-2021-0048692
(51) **LOC (15) Cl.** **14-04**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter illustrated by dashed broken lines in the drawings illustrates a display screen or portion thereof and forms no part of the claimed design. The remaining broken lines in the drawings illustrate portions of the graphical user interface that form no part of the claimed design.

1 Claim, 1 Drawing Sheet
